(57) **CLAIM**

The ornamental design for a split cover for a vehicle interior as shown and described.

DESCRIPTION

FIG. 1 is a front plan view of a first embodiment of a split cover for a vehicle interior having in accordance with the present design;

FIG. 2 is a back plan view of the first embodiment;

FIG. 3 is left and right side elevation views of the first embodiment;

FIG. 4 is a bottom elevation view of the first embodiment;

FIG. 5 is a top elevation view of the first embodiment;

FIG. 6 is a front plan view of a second embodiment of a split cover for a vehicle interior in accordance with the present design;

FIG. 7 is a back plan view of the second embodiment;

FIG. 8 is left and right side elevation views of the second embodiment;

FIG. 9 is a bottom elevation view of the second embodiment;

FIG. 10 is a top elevation view of the second embodiment;

FIG. 11 is a front and back plan views of a third embodiment of a split cover for a vehicle interior in accordance with the present design;

FIG. 12 is left and right side elevation views of the third embodiment;

FIG. 13 is a bottom elevation view of the third embodiment;

FIG. 14 is a top elevation view of the third embodiment;

FIG. 15 is a front and back plan views of a fourth embodiment of a split cover for a vehicle interior in accordance with the present design;
